[57] CLAIM

The ornamental design for a foglight lens, as shown and described.

DESCRIPTION

FIG. 1 is a top, front, right side perspective view of a foglight lens showing our new design, the automobile being fragmentarily shown in broken lines for illustrative purposes only;

FIG. 2 is a front view thereof;

FIG. 3 is a top view thereof;

FIG. 4 is a right side view thereof;

FIG. 5 is a left side view thereof;

FIG. 6 is a cross-sectional view thereof taken on the line 6—6 of FIG. 2 or a greatly enlarged scale.

FIG. 1.

FIG. 2.

FIG. 3.

FIG. 4.

FIG. 5.

FIG. 6.
